UNITED STATES PATENT OFFICE.

ALEXANDER McLEOD, OF BRISBANE, QUEENSLAND, AUSTRALIA.

TRIPOD-STAND FOR CAMERAS.

No. 821,052.

Specification of Letters Patent.

Patented May 22, 1906.

Application filed September 6, 1904. Serial No. 223,458.

To all whom it may concern:

Be it known that I, ALEXANDER McLEOD, a subject of the King of Great Britain and Ireland, and a resident of 171 Queen street, 5 Brisbane, in the State of Queensland, Commonwealth of Australia, have invented a certain new and useful Improvement in Tripod-Stands for Cameras and Such Like Articles, of which the following is a specification.

10 My invention relates to improvements in tripod-stands for cameras and such like articles, its object being to provide a self-contained tripod-stand in which the head is permanently fixed to the legs and which can be 15 folded up intact, always ready for immediate use, thus dispensing with the separate disk or base-plate upon which the camera rests and avoiding the necessity of connecting the legs or disconnecting same from the head, as required, also avoiding the use of a loose locking-screw.

20 The invention consists in permanently fixing to the top of the legs a head comprised of a central triangular-shaped metal plate with central hole, to each side of which is hinged 25 a rectangular metal plate pivotally connected to the top of the tripod-legs and which when spread out forms a base of suitable area upon which the camera rests.

30 Referring to the drawings, which form a part of this specification, Figure 1 is a plan view of the under side of the head with plates spread out; Fig. 2, a top plan of head; Fig. 3, a section through X X, Fig. 2; Fig. 4, an elevation; Fig. 5, a part-sectional elevation of modified arrangement. Fig. 6 is a sectional detail view of the same.

The reference-letters indicate like parts in all figures.

40 A is a triangular-shaped plate with central hole, hinged to which are three rectangular plates B, B', and B², folding over the central plate and meeting together, as shown in dotted lines. A locking-plate C is secured to the 45 triangular plate A by three clips b, b', and b², stamped out of the triangular plate A and bent over the edge of the locking-plate. c and c' are lugs formed integrally with the plate for turning same round, and d, d', and d² 50 slotted holes adapted to engage with studs e, e', and e², fixed onto the rectangular plates. A tightening-pin f, with thumb-piece f' and slightly-enlarged screwed end, is inserted through the central hole of the locking-plate

and triangular plate and prevented from dis- 55 engaging with the same by the increased size of the threaded end. This pin passes between the meeting-points of the rectangular plates, provision being made for same by the points being grooved out, as shown in Fig. 3, and 60 screws into the bottom of the camera, rigidly securing the camera to the tripod-head.

It is not necessary that the rectangular plates should bed perfectly upon the central plate, as any little play is taken up by the 65 tightening-pin when screwed into the bottom of the camera.

To fold up the stand, the locking-plate is turned round by the lugs c and c', which releases the studs e, e', and e², permitting the 70 rectangular plates to fold downward, as shown in Fig. 3.

In the modification illustrated in Figs. 5 and 6 I substitute for the locking-plate three links, of which two only show in the figure at 75 g g', owing to this figure being a sectional view. The links have their lower ends pivotally connected to projecting lugs on a collar k, rotatably held on the lower part of the pin h by the thumb-piece h', secured to the end of 80 the pin. The upper ends of the links are bent outwardly and connected to lugs g², secured centrally on the lower faces of the respective plates B, B', and B². The pin h has a threaded upper end h', which is designed to 85 screw upwardly through the threaded boss j and in the position shown in Fig. 5 projects through the threaded boss in position to be screwed into the camera to hold it to the tripod in the ordinary manner. In this position, however, it will be seen that the pin h 90 will be held up, retaining the links g g' in the locking position shown. If it be desired to fold up the tripod, the pin h will be unscrewed to cause its head h' to travel down through 95 the threaded boss j and be released therefrom, and while this is being done the plates B B' B² will rock upon pivots B³, by which they are connected to the central plate A, allowing the links g g', &c., to move downwardly and inwardly against the pin. Of course as soon as the threaded head h' has passed through the threaded portion of the boss j it may move 100 freely downward.

Having now described my invention, what 105 I claim as new, and desire to secure by Letters Patent, is—

A tripod for cameras and the like compris-

ing a stationary central plate, rectangular plates for carrying the tripod-legs hinged to said central plate, said rectangular plates being adapted to extend over the central plate 5 when in operative position, a tightening-screw passing through the central plate to engage the camera and means independent of said screw for holding the rectangular plates

in their extended position on the central plate.

In witness whereof I have hereunto set my hand in presence of two witnesses.

ALEXANDER MCLEOD.
